UNITED STATES PATENT OFFICE.

WILLIAM H. MORRIS, OF ROSLINDALE, MASSACHUSETTS.

DESIGN FOR A NUT-BOWL.

51,148.

Specification for Design.

Patented Aug. 14, 1917.

Application filed May 12, 1917. Serial No. 168,291. Term of patent 7 years.

To all whom it may concern:

Be it known that I, WILLIAM H. MORRIS, a citizen of the United States, residing at Roslindale, in the county of Suffolk and Commonwealth of Massachusetts, have invented a new, original, and ornamental Design for a Nut-Bowl, of which the following is a specification, reference being had to the accompanying drawing, forming a part thereof.

Figure 1 is a perspective view of a nut bowl showing my new design; and Fig. 2 is a side elevation thereof.

I claim:

The ornamental design for a nut bowl as shown.

WILLIAM H. MORRIS.
